UNITED STATES PATENT OFFICE.

LOUIS F. WESCHE, OF WEBB, IOWA.

SIGNAL.

1,254,752.

Specification of Letters Patent. Patented Jan. 29, 1918.

Application filed June 23, 1917. Serial No. 176,612.

To all whom it may concern:

Be it known that I, LOUIS F. WESCHE, a citizen of the United States, residing at Webb, in the county of Clay and State of Iowa, have invented certain new and useful Improvements in Signals, of which the following is a specification, reference being had to the accompanying drawings.

This invention relates to certain improvements in signals and has relation more particularly to a device of this general character especially adapted and designed for use in connection with vehicles to give indication of the direction in which a turn is to be made, and it is an object of the invention to provide a novel and improved device of this general character comprising a plurality of curtains normally maintained in a retracted position but which may be readily extended 20 when the requirements of practice necessitate.

Furthermore it is an object of the invention to provide a device of this general character having novel and improved means whereby the curtains may be held in an extended position together with means for automatically retracting said curtains upon release of the holding means.

The invention consists in the details of construction and in the combination and arrangement of the several parts of my improved signal wherein certain important advantages are attained and the device rendered simpler, less expensive and otherwise 35 more convenient and advantageous for use, as will be hereinafter more fully set forth.

The novel features of my invention will hereinafter be definitely claimed.

In order that my invention may be the better understood I will now proceed to describe the same with reference to the accompanying drawings wherein—

Figure 1 is a view partly in elevation and partly in section illustrating a signal constructed in accordance with an embodiment of my invention and in applied position with one of the curtains extended;

Fig. 2 is a sectional view taken substantially on the line 2—2 of Fig. 1;

Fig. 3 is a sectional view taken substantially on the line 3—3 of Fig. 2;

Fig. 4 is a sectional view taken substantially on the line 4—4 of Fig. 1; and

Fig. 5 is a fragmentary view partly in elevation and partly in section of one of the winding rollers as herein included.

As disclosed in the accompanying drawings S denotes a supporting standard or upright as generally employed upon a motor driven vehicle for supporting a windshield and extending laterally and outwardly from said standard or upright are the vertically spaced brackets B suitably clamped to the standard or upright as indicated at 1. The outer portions of the brackets B are engaged with the housing H substantially rectangular in form and which has its front and rear ends provided with the windows 2 closed by the panels 3 of glass or other transparent material. Extending upwardly from the base 4 of the housing H at substantially its center is an illuminating member 5 preferably of an electrical type and in connection with a suitable source of electrical energy through the medium of the conductors 6. Positioned within the housing H adjacent the front and rear ends thereof and in close proximity to the top of the housing are the substantially horizontally aligned rollers 7 and 8 and the roller 7 is of a conventional spring winding type as indicated in detail Fig. 5 while the second rollers 8 serve as a guide member. Positioned below the rollers 7 and 8 are a second set of transversely disposed rollers 7^a and 8^a, the roller 7^a being also of a spring type. Secured to each of the rollers 7 and 7^a are the end portions of a pair of opaque webs 9 and 9^a. The free end portions of the webs 9 and 9^a co-acting with the roller 7 are cut out to afford a suitable character 10 preferably the letter "R" and said cut out portion affording the character 10 is closed by a transparent fabric 11 preferably red in color so that when the free end portions of the webs 9 and 9^a co-acting with the roller 7 are extended to overlie the windows 2 indication will be given that the vehicle is about to turn to the right. The free end portions of the webs 9 and 9^a co-acting with the roller 7^a are similarly provided with characters preferably the letter "L" which serve, when the free end portions of the second set of webs 9 and 9^a are extended over the windows 2, to give indication that the vehicle is about to turn to the left. The web 9 of the roller 7 is disposed over the guide roller 8 so as to properly co-act with the window 2 remote from the roller 7 while the web 9 co-acting with the roller 7^a is disposed over the guide roller 8^a for a similar purpose.

The free end portion of the webs 9 and 9^a

are each secured to a transversely disposed rod 12 terminating in eyes 14 positioned beyond opposite sides of the web and which loosely engage the vertically disposed guide rods 15 arranged within the housing H, adjacent the sides thereof. The extended portions of the rods 12 of each pair of webs 9 and 9^a are connected by the longitudinally disposed rods 16. Depending from one of each of the pairs of rods 16 is a hook member 17 having engaged therewith a flexible member 18 or the like which extends exteriorly of the housing H through an opening or slot 19 produced in the bottom or base 4 of said housing. It will be at once self evident that upon pulling downwardly upon one of the members 18, the free end portion of a pair of webs 9 and 9^a will be extended to cause the same to overlie the windows 2.

When the webs have been extended to the limit of their extended movement the hook member 17 is engaged by the latch arm 20 for maintaining said webs extended. The arm 20 is pivotally mounted at its inner end as indicated at 21 to the plate 22 substantially secured to the base or bottom 4 of the housing and is constantly urged in one direction through the medium of the retractile member 23 herein disclosed as a conventional coil spring secured at one end to the upturned extremity 24 of the arm 20 and its opposite end to a side wall of the housing H as particularly illustrated in Fig. 2. The retractile member 23 serves to limit the relative movement of the latch arm 20 and the influence of the retractile member 23 is limited by the upstanding pin or stop 25 carried by the plate 22 and which is so positioned as to assure the lock arm 20 to automatically engage the hook member 17.

Also operatively engaged with the upstanding portion 24 of the arm 20 is a rod 26 extending exteriorly of the housing H through an end thereof and which has its outer end provided with a button 27 to facilitate imparting inward movement to the rod 26. When the rod 26 is forced inwardly it will be at once self evident that the latch arm 20 will be disengaged from the hook member 17 whereupon the extended webs 9 and 9^a will be automatically retracted by the spring rollers 7 or 7^a.

The free end portion of the latch arm 20 is held against upward movement by the clip 28 secured to the bottom or base 4 of the housing H and partially overlying the latch arm 20 as particularly illustrated in Figs. 2 and 3. It will also be understood that the clip 28 serves to limit the movement of the latch arm 20 under the influence of the rod 26.

From the foregoing description, it is thought to be obvious that a signal constructed in accordance with my invention is particularly well adapted for use by

reason of the convenience and facility with which it may be assembled and operated and it will also be obvious that my invention is susceptible of some change and modification without materially departing from the appearance and spirit thereof and for this reason I do not wish to be understood as limiting myself to the precise arrangement and formation of the several parts herein shown in carrying out my invention in practice except as hereinafter claimed.

I claim:

1. A signal comprising a housing provided with visual openings in opposite walls thereof, a pair of transversely disposed rollers positioned within the housing, one of said rollers automatically rotating in one direction, a pair of webs secured to the automatically rotating roller, one of said webs being disposed over the second roller, means co-acting with the webs for extending the same over the visual openings, and releasable means for locking said webs against the action of the automatically rotating roller.

2. A signal comprising a housing provided with visual openings in opposite walls thereof, a pair of transversely disposed rollers positioned within the housing, one of said rollers automatically rotating in one direction, a pair of webs secured to the automatically rotating roller, one of said webs being disposed over the second roller, means co-acting with the webs for extending the same over the visual openings, releasable means for locking said webs against the action of the automatically rotating roller, and means extending exteriorly of the housing for rendering said releasable means inoperative.

3. A signal comprising a housing provided with visual openings in opposite walls thereof, a pair of transversely disposed rollers positioned within the housing, one of said rollers automatically rotating in one direction, a pair of webs secured to the automatically rotating roller, one of said webs being disposed over the second roller, means co-acting with the webs for extending the same over the visual openings, releasable means for locking said webs against the action of the automatically rotating roller, and guide members positioned within the housing and co-acting with the free end portions of the webs.

4. A signal comprising a housing provided with visual openings in opposite walls thereof, a pair of transversely disposed rollers positioned within the housing, one of said rollers automatically rotating in one direction, a pair of webs secured to the automatically rotating roller, one of said webs being disposed over the second roller, rods carried by the free end portions of the webs and disposed transversely thereof, a rod

connecting the first named rods, and means co-acting with said last named rod for extending the webs across the visual openings. 25

5. A signal comprising a housing provided with visual openings in opposite walls thereof, a pair of transversely disposed rollers positioned within the housing, one of said rollers automatically rotating in one direction, a pair of webs secured to the automatically rotating roller, one of said webs being disposed over the second roller, rods 30 carried by the free end portions of the webs and disposed transversely thereof, a rod connecting the first named rods, means co-acting with said last named rod for extending the webs across the visual openings, said 35 first named rods terminating in eyes, and vertically disposed members arranged within the housing and disposed through the eyes of the first named rods.

In testimony whereof I hereunto affix my 40 signature in the presence of two witnesses.

LOUIS F. WESCHE.
